UNITED STATES PATENT OFFICE.

JOHN EDWARD TRACY, OF ORLANDO, FLORIDA.

CONTAINER FOR CEDAR SHAVINGS.

1,368,861.

Specification of Letters Patent. Patented Feb. 15, 1921.

Application filed February 14, 1920. Serial No. 358,635.

To all whom it may concern:

Be it known that I, JOHN EDWARD TRACY, a citizen of Orlando, in the county of Orange and State of Florida, have invented certain new and useful Improvements in Containers for Cedar Shavings, of which the following is a specification.

My invention relates generally to boxes and particularly to a container for cedar shavings or the like which is comparatively small to permit of its being placed in a trunk or other clothes receptacle for preventing moths from attacking the clothes.

A purpose of my invention is the provision of a container of the above described character which will allow of the exposing of the cedar shavings to the air while at the same time preventing the shavings from being displaced from the container.

It is also a purpose of my invention to provide a container which comprises sections so interfitted as to eliminate the use of nails or other fastening members for securing the sections together.

I will describe one form of container embodying my invention and will then point out the novel features thereof in claim.

In the accompanying drawings:

Figure 1 is a view showing in perspective one form of container embodying my invention.

Fig. 2 is a transverse sectional view of Fig. 1.

Fig. 3 is a detail view showing the inner side of one of the end sections.

Fig. 4 is a detail fragmentary view showing in plan a portion of one of the end members.

Referring specifically to the drawings, in which similar reference characters refer to similar parts, S and S' designate the side sections of the container which as shown to advantage in Fig. 2 are provided upon

their confronting faces with longitudinally extending grooves 15 and 15^a, the upper grooves 15 of which coat to slidably receive a foraminous top section T while the lower grooves 15^a coat to slidably receive a bottom section B. The sections S and S' are connected at their ends by end sections E and E'. As shown in Fig. 3, each end section E or E' is provided on its inner side with vertically extending grooves 16 and

horizontally extending grooves 17, all of such grooves being formed at the mar-

ginal edge of the section in such manner as to provide flanges 16^a and 17^a, respectively.

As shown in Fig. 1, the opposite ends 60 of each side section S or S' are integrally formed with vertically extending ribs 18 which are adapted to snugly fit within the vertical grooves 16 of the end sections E and E'. It will be particularly noted that 65 the ribs 18 are formed on the side sections E and E' in such manner as to provide a shoulder 19 at one side of the ribs, such shoulder in the assembled position of the sections contacting with the flanges 16^a of 70 the end sections E and E'.

The end sections E and E' are permanently secured to the side sections S and S' by inserting a film of glue between the confronting faces of the shoulders 19 and the 75 parts 16^a. Prior to the gluing of one end section to the side sections, however, the bottom section B is inserted into the grooves 15^a with its opposite ends disposed within the horizontal grooves 17 of the end sections in 80 such manner that the flanges 17^a prevent outward lateral movement of the bottom section and thereby lock the same to the end and side sections.

After the bottom section has been placed 85 in position, the foraminous top section T is now applied, it being readily insertible into the grooves 15 of the side sections and into the upper groove 17 of the end section. The container is now filled with cedar shavings 90 as indicated at C in Fig. 2 whereupon the remaining end section is applied so that the adjacent end of the top section T extends into the upper groove 17 thereof, the adjacent end of the bottom section B extending 95 into the lower groove 17 thereof, and the adjacent ends of the side sections extending into the vertical groove 16. In the present instance, the member T is formed of wire screen so that the cedar shavings will be 100 free to permeate the surrounding atmosphere with their aroma. Thus when the container is placed within a trunk or other closed receptacle, the aroma from the cedar shavings is free to permeate the latter and 105 to thereby prevent the nesting of moths within the clothes. As a further aid to this end, the sections comprised in the container are preferably formed of cedar, although it is to be understood that they may be 110 formed of any other suitable material.

In the present embodiment of my inven-

tion I have shown the foraminous member T formed of wire screen but it is to be understood that it may be formed of any suitable material which will permit the circulation of air to and from the interior of the container.

Although I have herein shown and described only one form of container embodying my invention, it is to be understood that 10 various changes and modifications may be made herein without departing from the spirit of the invention or the spirit and scope of the appended claim.

What I claim is:—

15 A container of the character described comprising, side sections having grooves

formed therein at corresponding points, ribs formed on the opposite ends of said sections, end sections having their confronting sides formed with vertically extending grooves 20 and horizontally extending grooves between and in a different vertical plane with respect to the first grooves, a bottom section fitted within the grooves of the side sections, and certain of the horizontal grooves of the end 25 sections, and a top section fitted within the grooves of the side sections and within certain of the horizontal grooves of the end sections, said side and end sections being associated in such manner that the ribs fit with- 30 in the vertical grooves of the end sections.

JOHN EDWARD TRACY.
